DOOR CHECK

Samuel T. Alexander, Redondo Beach, Calif., assignor of one-third to Paul Eddy Richardson, Los Angeles, Calif.

Application January 7, 1946, Serial No. 639,532

9 Claims. (Cl. 16—51)

1

My present invention relates to a door check, and more specifically to a door check which not only will check the closing action of a door, but also will check the fully open positioning of the door to which the device is attached. Also, it will hold the door in a fully open position after bringing the door gently to a stop in such fully open position.

Numerous hydraulic door checks have been devised which will close a door and hold it in closed position. One such effective type of door check is disclosed in my Patent No. 2,318,041, issued May 4, 1943. This and other prior types of door checks, while they may latch the door in an open position at substantially right angles to their closed position, are not adapted to the moving of the door to a fully opened position to lie along a wall in which the door is mounted. Also, they are not arranged to check the opening action of the door by the same checking mechanism which checks the closing of the door. Such an arrangement is desirable for example in filling stations, where a door is mounted in a wall adjacent an automobile driveway. In such a location if the door is left ajar at an angle of approximately 90° to the wall in which it is mounted, it is apt to be struck by a passing automobile. Aside from such danger, a door held in such a 90° position frequently is in the way of those working near it.

An object of the present invention is to make an improved door check.

Another object is to make a door check having a hydraulic cylinder and a spring actuated piston connected to a door by a bracket so that the device will act as a door closer and door check in the closed position, and also as a door opener and door check in a fully open position.

Another object is to make a door check with a hydraulic cylinder and integral liquid storage reservoir pivoted to one unit of a door and frame combination, and a hydraulic piston connected to the other unit of the combination so that the device will act as a hydraulic check and door closer up to a predetermined angle of door opening movement and beyond that point will act as a hydraulic check and door opener up to an opened angle of approximately 180° from the door's closed position.

In order to attain these objects, there is provided, in accordance with one feature of the invention, a hydraulic cylinder with a spring actuated piston mounted therein and connected, by a piston rod to a door bracket, the door bracket being so positioned in relation to a door and its

2

frame upon which the door check is mounted as to act as a closing door check when the door is opened less than a predetermined amount, and to act as an opening door check when the door is opened beyond such amount, the same checking mechanism acting in a similar manner for both the opening and the closing checking operation.

These and other objects of the invention will be apparent from the following description and the accompanying drawings, which disclose a preferred form of my invention.

In the drawings:

Fig. 1 is a vertical sectional view through a door closer embodying the present invention as it would appear mounted on a door and casing, the door and casing being shown fragmentarily;

Fig. 2 is a sectional view taken on line 2—2 of Fig. 1; and

Fig. 3 is a sectional view similar to Fig. 2, but with the door in fully open position.

Referring to the drawings in detail, a door 10 is hinged in a door casing 11 as on butt hinges 12. A door check housing 13 has an end plate 18 which is pivoted on a post 14 of a mounting plate 15. The mounting plate is set in a recess cut in the head of the door casing 11 so as to lie flush with the surface of the head, and is secured in position by screws 16. A retaining screw 17 holds the end plate 18 on the post 14.

A cylindrical tube 20 is mounted in the lower part of an oval body portion 19 of the housing 13, the ends of the tube 20 being gripped between the end plate 18 and an opposite end plate 21. The cylinder 20 has a slotted opening 22 extending approximately one-half the length of the upper side of the tube 20. The function of this slotted opening will be brought out later in the specification.

A hollow or tubular piston 23 is mounted within the tube 20 to have a sliding fit therein, and a ball check 24 is mounted in the right hand end of the piston 23. The ball check 24 is mounted to seat on a valve seat 25 formed in the piston. A liquid control passage 27 connects the right hand end of the cylinder 20 to the interior of the housing 13 above the cylinder, and a needle valve 28 is mounted to control the flow of fluid through the passage 27.

A bracket 29 connects the left hand end of the piston 23 to a piston connecting rod 30 which projects outwardly through the end 21 of the housing 13 and is bent downwardly as at 31. The bracket rides in the slot in the upper side of the cylinder 20. The downwardly bent end portion

31 of the rod 30 is pivoted in an opening in a bracket 32 which is secured to the door 10 by screws 33.

The bracket 32 to which the rod 31 is pivoted is mounted on the inside or closing side of the door and is of such a length as to extend laterally beyond the plane of the hinged edge of the door. One or more additional pivot openings 36 may be provided in the extending portion of the bracket 32 beyond the plane of the door edge so that the downturned end portion 31 of the rod 30 may be pivoted in any of these openings, thereby varying its position relatively to the edge of the door and the pintle of the hinge 12. Such variation of the point of pivotal connection of the rod 30 with the bracket 32 will change the angle at which the change from door opening to door closing action occurs.

An opening 34 is provided in a side door frame member or jamb 42 to receive the end of the bracket 32 when the door moves to the closed position. Preferably a thimble 35 is inserted in the hole 34 to seal off the hole and to provide a decorative trim for it.

A coil spring 37 is connected between the bracket 29 and the end plate 21 of the housing 13 so as normally to draw the bracket and its connected piston 23 and rod 30 to the limit of their extended, or right hand movement. A quantity of hydraulic fluid 38 is provided in the housing 19, the fluid being of a depth to slightly more than cover the cylinder 20.

When the door is in the closed position illustrated in Fig. 2, the tension of the spring 37, acting on the bracket 32 tends to retain the door to the closed position. When the door is opened, however, the bracket will move clockwise about the pintle of the hinge 12, thereby moving the rod 30 leftward from the position illustrated in Fig. 1. This action moves the piston 23 to the left from the position illustrated in Fig. 1, extending the spring 37 and causing the fluid 38 in the housing to flow through the hollow piston, through the valve seat 25, past the ball check 24 and out of the right hand end of the piston.

If the door is released before the downturned end 31 of the rod 30 passes a straight line (indicated by the numeral 39 in Fig. 3), between the centers of the pivot post 14 and the pintle of the hinge 12, the tension of the spring 37 will return the door to closed position. On moving to the closed position the ball check 24 will seat on its seat 25 and force liquid trapped between the ball check and the end plate 21 through the liquid control passage 27. The flow of liquid through the passage 27 may be controlled by adjustment of the needle valve 28. If, however, the door is opened beyond the straight line of centers position 39, the tension of the spring 37 will tend to force the door to a fully opened position, as illustrated in Fig. 3.

Here again, in moving to the fully open position, the fluid check will operate in the same manner as when the device is moving the door to the closed position, and will prevent the door from slamming against a wall in which the door frame is mounted. It is apparent, therefore, that with no additional latches or mechanisms the door is hydraulically checked both in opening and closing, and the door may be fully opened, and retained in fully opened position merely by moving the door beyond the point where the centers of the pintle of the hinge 12, the pivot pin 14 and the end portion 31 of the rod 30 are in alignment with each other.

While I have illustrated and described a preferred embodiment of my invention, it will be understood by those familiar with the art that some modifications can be made without departing from the spirit and scope of the invention. It is desired, therefore, not to limit the invention except as defined in the appended claims.

I claim:

1. A two-way acting door check for a hinge mounted door comprising an extensible unit spring pressed to extended position, means mounted to check a spring pressed extending movement thereof, a pivot adapted pivotally to connect one end of the extensible unit to a door frame within a door opening in said frame, a bracket adapted to be secured to a door hingedly mounted on a side of the door opening, the bracket extending beyond the plane of the door's hinged edge, and a pivot connecting the extending portion of the bracket to the other end of the extensible unit.

2. A two-way acting door check for a hinge mounted door comprising an extensible unit spring pressed to extended position, hydraulic check means mounted to check a spring pressed extending movement thereof, a pivot adapted to connect one end of the extensible unit within the door opening in a door casing, a bracket adapted to be secured to a door hingedly mounted on a side of said casing to have a portion of said bracket extend beyond the plane of the door's hinged edge, and a pivotal connection between the bracket at a point beyond said edge plane and the other end of the extensible unit.

3. An opening and closing check for a door hingedly mounted in a casing, comprising: a spring loaded extensible door actuator, pivotal means adapted to connect one end of the actuator to a door casing, and a bracket adapted to be fixedly mounted on a door, the bracket having an elongated portion adapted to extend into a recess in the door casing, the door actuator being pivotally connected to the elongated portion of the door mounted bracket at a point which will enter the recess when a door on which the bracket is mounted is in a closed position.

4. An opening and closing check for a door hinge mounted in a door casing, comprising: a housing adapted to be pivotally connected to a door casing, an extensible rod carried by the housing, a bracket adapted to be fixedly mounted on a door, hingedly mounted in the casing, to have a portion of said bracket extend beyond the plane of a hinged edge of a door on which it is mounted, a pivotal connection between the extensible rod and the bracket at a point on the bracket laterally beyond said door edge plane, and inwardly offset from a line joining the pivotal connection of the housing with the door casing and the door hinge axis, the pivotal connection between the rod and the bracket being adapted to swing outwardly beyond said joining line on an opening of the door beyond a predetermined amount, and a spring acting between the rod and the housing to urge the pivotal connection of the rod to the bracket away from the pivotal connection for the housing and door casing.

5. A two-way door check for a door hingedly mounted in a casing having a side recess therein, comprising: a bracket adapted to be mounted on a door and having a portion thereof adapted, when the door is closed, to enter a recess in a door casing side member on which the door is hingedly mounted, and a checking device having

one end thereof adapted to be pivotally connected to a top door casing member and the other end thereof pivotally connected to the bracket at a point adapted to enter said recess.

6. A two-way door check for a door hingedly mounted in a door casing, having a recess in a side thereof, said mounting comprising: a rigid housing, pivot means adapted to connect one end of the housing to a door casing, a rod mounted for free endwise movement in the housing, a spring connected to the rod and to the housing to urge the rod to extended position relatively to the housing, a hydraulic checking device operatively connected between the rod and the housing to resist rapid extending movement of the rod, a bracket adapted to be mounted on a door to have a portion of the bracket extend beyond the plane of the hinged edge of the door and enter a recess in the door casing, and a pivotal connection between the rod and the bracket at a point adapted to enter said recess.

7. An opening and closing device for a door hingedly mounted in a door casing having a recess in a side thereof, comprising: a spring loaded extensible member, a pivotal connection adapted to connect one end of said extensible member within a door casing and a bracket adapted to be mounted on such door, said bracket having a portion thereof adapted to extend laterally beyond the plane of the hinged door edge to enter the recess in the door casing, and adjustable pivotal connecting means connecting the other end of the extensible member to the bracket at any of a plurality of points on the portion of the bracket adapted to enter the recess, the latter pivotal connecting means being changeable to vary the location of the pivotal connection with respect to the plane of the door edge and of the axis of the hinged mounting of the door, thereby to vary the opening and closing characteristics of the device.

8. The combination with a door casing having

a side recess therein, a door, and hinge means hingedly supporting the door in the casing; of an extensible member comprising a hydraulic cylinder pivoted within the door casing, a hydraulic piston operatively mounted in the cylinder, a piston rod carried by the piston and extending beyond the cylinder, a spring mounted in compression between the piston and a cylinder element resiliently to urge the piston rod outwardly of said cylinder, a bracket mounted on the door and extending into the recess in the casing when the door is closed, and a pivotal connection between the piston rod and the extending portion of said bracket.

15 9. The combination with a door casing having a side recess therein, a door hingedly mounted on a side of the casing to open outwardly therefrom; of a door check comprising an extensible element, spring means resilient urging said extensible element to an extended position, a pivot connecting an end of said extensible member to the door casing at a point inwardly of said door relatively to its direction of opening, a bracket mounted on the inner side of said door and having a portion thereof extending laterally beyond the hinged edge of said door, and a pivotal connection between the other end of the extensible member from that connected to the door casing and said bracket at a point laterally beyond the 20 hinged edge of said door.
